BRANDT & C.W. WARNICK Assignees of S.H. SAILOR. 4-26-1853
Planted 26th April 1853.

DES 558

AN IRON COOKING STOVE, CALLED THE "CAPITOL".

118.

558

Samuel H. Sailor, of Philadelphia, Pa.

Assignor to

C. W. Warnick & F. Leibrandt, of Philadelphia aforesaid.

Letters Patent, No. 558 - Dated Apr. 26th 1853.

.....

The schedule referred to in these Letters Patent and making part of the same

.....

To all whom it may concern:

Be it known, that I, Samuel H. Sailor, of the City and County of Philadelphia, and State of Pennsylvania, have invented or produced a new and original design in Cook Stoves, denominated

"The Capitol".

and I do hereby declare that the following is a full, clear, and exact description of the same, reference being had to the annexed drawings forming part of this specification, in which.

Figure 1, is a side elevation of the stove and feet.

Figure 2, is a front elevation, showing the design of one door, the other being similar, is not given.

Figure 3, is a rear elevation.

In the several figures where the ornament is symmetrical, but one half is given.

Similar characters indicate the same parts.

The doors A, in front of the stove are raised above the surface of the front plate by the moulding formed by the ovolu a, and cavetto b, and the panel of each enclosed by the bead c, and ornamented on its upper portion by the sweeps d, foliage f, and elliptical figure e, in bas-relief arranged as shown in figure 2; in the lower part of the panels are the usual draft openings h.

On each side of the stove are the oven doors B, and C, each surrounded by mouldings similar to those of the doors A. Upon the panel of the door C are the sweeps i, foliage k, and elliptical and globular figures m, and n, in bas-relief, having the configuration and arrangement and forming the ornamental design seen in figure 1; and on the panel of the door B, the combination of foliage

D

Res. 558

o, sweeps p, and elliptical and spherical figures q, and q', seen in figure 1.

The portion of the side plates F, above the doors B, is on one side occupied by the feed door D, the top and sides of which are enclosed by the moulding E, similar to the mouldings above described, while the bottom flares outward to cover the feed projection on the plate, the corresponding part of the opposite plate has a raised panel of the same size as the door D, surrounded by a moulding similar to that upon the other doors: the door D, and opposite panel each bear the ornamental design G, in bas-relief formed of the sweeps r, foliage s, globular figures t, and elliptical figure u, arranged as shown in figure.

The bed plate K, is ornamented by the scroll and arched ornaments w, arranged as shown in figure 1. Upon each of the side plates above the door C, is the inscription "Warwick & Leibrandt 1853." in raised capitals and numerals, each inscription enclosed by the bead O.

The foot P, is of the form seen in figure 1, and is ornamented by the leaf Q, scrolls R, and S, (the latter representing toes) and sweeps T, having the arrangement and configuration shown in the drawing.

Upon the back W, of the stove, are the double arched ornaments in bas-relief, a', b', c', arranged and having the configuration shown in figure 3.

What I Claim as my invention, or production and desire to secure by Letters Patent, is

The configuration and arrangement of the ornaments in bas-relief, upon the doors A, B, C, and D, side plates F, bed plate K, back W, and feet P, as described in this specification and the annexed drawings, forming a new and original design for cook stoves, designated as "The Capitol."

In testimony whereof, I have hereunto signed my name before two Subscribing Witnesses.
